HEADGEAR FOR WRESTLERS

Bobby E. Douglas, 8 Boyd Ave.,
Bridgeport, Ohio 43912

Filed June 8, 1970, Ser. No. 23,363

Term of patent 14 years

Int. Cl. D2—03

U.S. Cl. D2—232

FIG. 1 is a perspective view of a headgear for wrestlers showing my new design,

FIG. 2 is a side view thereof,

FIG. 3 is a top view thereof,

FIG. 4 is a bottom view thereof, and

FIG. 5 is a view of one of the like inner sides taken on the line 5—5 of FIG. 1.

I claim:

The ornamental design for a headgear for wrestlers, as shown.
